UNITED STATES PATENT OFFICE.

GLENN HENRY BOLUS, OF MANSFIELD, OHIO, ASSIGNOR TO THE OHIO BRASS COMPANY,
OF MANSFIELD, OHIO, A CORPORATION OF NEW JERSEY.

MINE SECTION INSULATOR SWITCH.

1,129,062.

Specification of Letters Patent. Patented Feb. 23, 1915.

Application filed February 20, 1914. Serial No. 819,895.

To all whom it may concern:

Be it known that I, GLENN H. BOLUS, a citizen of the United States, residing at Mansfield, in the county of Richland and State of Ohio, have invented certain new and useful Improvements in Mine Section Insulator Switches, of which the following is a specification.

My invention relates to improvements in section insulators and has more particular reference to section insulator switches of the character used most generally in mines and similar places.

One of the objects of my invention is to provide an improved device of this character which will be simple, durable and reliable in construction and effective and efficient in operation.

Other objects of my invention will appear hereinafter.

Referring to the drawings: Figure 1 is a view in elevation of an insulator switch structure embodying my invention. Fig. 2 is a bottom plan view thereof. Fig. 3 is a longitudinal horizontal section on the line 3—3 of Fig. 1. Fig. 4 is a transverse section on the line 4—4 of Fig. 1. Fig. 5 is a transverse section on the line 5—5 of Fig. 1, and Fig. 6 is a detail view of the inner end portion of one of the end members of the device.

In the structure shown in the drawings the parts are generally supported by the long rectangular-shaped beam or bar A, which is preferably made of insulating material, such as wood, and which serves as the insulating medium between the end members B. The end members B, to which the terminals or ends of the section of the trolley wire are attached, are preferably made in the form of castings which are secured to the under edge of the insulating beam A adjacent its end portions by means of the long bolts 1. The beam A is positioned on edge for strength, and the bolts 1 pass through from the top edge of the member A to the lower edge where they are screwed into the metal of the end castings and thus securely fasten the parts together and hold them in proper alignment. The end members B are preferably hollow and are rounded off on their under edges similar to the shape of a trolley wire so as to form a smooth underrun surface for the contactor

wheels on the poles of the cars. These end members have end runner pieces 2 which are integrally formed therewith and which project beyond the ends of the insulating beam A and which are rounded off on their under sides flush with the end members B so as to likewise provide smooth underrun surfaces for the contactor. These end runners have longitudinal grooves 3 which open on their lower sides, for a portion of the length thereof, for the reception of the end portions of the trolley wires which are to be connected thereto. The lips or edges 4 of these grooved end runner pieces are preferably thin and are bendable so that they may be formed around the trolley wire in such manner as to substantially merge with the surface of the trolley wire in order to avoid bumps, so to speak, in the continuity of the trolley wire. The grooves 3 of the end runners incline slightly upward at their inner end portions and a number of set screws 5 are provided for clamping the trolley wire firmly in position. The end members B have short upstanding projections 6 adjacent the ends of the beam A, and these projections are provided with transverse holes 7 and set screws 8 for the purpose of attaching feeder wires to the structure. I also provide suspension members 9 on the upper edge of the beam A adjacent its ends. These suspension members 9 have clevises 10 which embrace the beam and are secured thereto by transverse bolts 11, and said members are also provided with threaded sockets 12 which may be secured to hanger members (not shown) of the ordinary or any suitable type for the purpose. It will be noted that this arrangement provides a two-point suspension for the structure and has the advantage over the ordinary single point suspension of preventing the structure from wabbling.

The inner ends of the end members B terminate considerably short of each other so as to provide a space therebetween, and this space is adapted to be filled by a rotary underrun piece or member 13. This member is formed similar to the end members B in so far as it serves to fill in said space between said end members; that is to say, it is hollow and it is rounded off on its under edge similarly to the end members B and flush with the underrun surface of the

end members so that when it is rotated to a position in alinement with said end members it forms a complete continuation thereof and enables the trolley wire to pass smoothly from one end member to the other. The member 13 is preferably made of metal, instead of wood or other softer materials generally used so that it will effectively withstand wear.

10 It will be noted, more particularly by reference to Figs. 1, 2 and 6, that the inner ends of the end members B and the corresponding co-acting ends of the member 13 are cut on the bias so as to insure the proper alinement of said member 13 with the end members B when the member 13 is rotated to its alined position. When the member 13 is rotated to a position at right angles to its bridging position, as shown in the dotted 15 lines in Fig. 2, the space between the end members B will be effectively open and the trolley contact wheel cannot pass smoothly. The underrun piece or member 13 has a flat circular horizontally disposed disk or plate 20 14 formed at the central portion of its upper edge, and this disk or plate 15 co-operates with a similar disk or plate 15 to form, in a sense, a turn-table or bearing for the bridge member 13. These co-operating disks, it will be 25 noted, are comparatively large in diameter and consequently provide a great bearing surface which very effectively insures the proper operation of the member 13 and prevents it from becoming wabbly or relatively 30 displaced in any manner. The stationary bearing disk 15 has a number of up-standing projections or ears 16 which are spaced apart so that the beam A may be positioned therebetween, and these ears are clamped 35 securely to the beam A by bolts 17 which pass through said ears and through the beam A, as clearly shown in Fig. 5. The two bearing disks 14, 15 are held in contact by means of a central pivot bolt 18 which passes 40 down from the upper side of the disk 15, through said disk 15 and is threaded into the metal of the member 13. After the bolt has been screwed into said member 13 it is held locked against relative rotation with 45 respect thereto by means of a transverse pin 19. In order that the two bearing disks 14, 15 may be held firmly, and at the same time 50 yieldingly in contact, I interpose a spring collar or washer 20 between the head 21 of 55 the bolt and the upper face of the disk 15, and if desired, a flat washer 22 may be also placed below the spring washer 20 for the purpose of taking up the wear. The beam A is, of course, provided with a socket or 60 hole 23 to provide room for the bolt head 21 and spring washer 20.

A handle of any suitable type, such as the handle C, may be provided for operating the member 13. One end of this handle is 65 secured to an angular integral projection 24

outstanding laterally from the member 13 near one end thereof so that the handle will stand cut at an angle from the device, and thereby in such position that it may be conveniently reached and operated without the necessity of the operator coming in contact with the live parts of the device. As a further protection for the operator a large disk or plate 25 is positioned at the inner end of the handle and serves as a guard.

75 The rotary member 13, which I have described, serves to effectively close or open the space between the end members B from a mechanical standpoint; that is to say, it is intended to form a mechanical continuation 80 of said end members B when it is rotated into alinement therewith. While it may, if desired, serve also to electrically connect said end members together, I prefer to employ additional means for this purpose, and 85 this additional means is so positioned that it cannot be struck or disturbed by the trolley contactor wheel. In the structure shown I electrically connect the end members B by means of a flat rectangular switch 90 blade 26 positioned above the member 13. This switch blade has a central hole through which the pivot bolt 18 passes, and it is laid in a flat groove which is milled in the upper face of the bearing disk or plate 14, as 95 clearly shown in Fig. 5. This blade, however, is firmly secured to and movable with the member 13 by means of the bolts or screws 27 which clamp the blade against 100 standing lugs or projections 28 on the member 13 near the ends thereof. This switch blade is disposed at a slight angle with respect to the member 13, as shown clearly in Figs. 2 and 3, and its ends are adapted to enter between and engage stationary spring 105 clips 29 which are positioned above the inner ends of the end members B. These clips are preferably in the form of flat pieces of metal having their inner ends 110 embedded in grooves formed in the end members B, said clips being locked in position by transverse pins 31, as clearly shown in Fig. 4. The clips on each end member B are spaced apart to provide a suitable entrance for the end of the switch blade 26. 115 The switch blade and its co-acting clips thus serve to very effectively electrically connect and disconnect the end members B at two points, thus reducing the tendency to arc and at the same time these parts are positioned above the path of movement of the trolley contactor wheel so that there is no danger of damage therefrom. My improved structure also permits repairs there- 120 to when the rotary parts are in open position because in open position these parts are electrically dead and the operator or repairman will not receive a shock when working on said parts. The construction of the inner ends of the end members is such that 125 130

even should a trolley wheel pass when the device is open, no damage will be done either to the wheel or the structure. These inner ends are open so that when the device is being installed the trolley wire may be pulled through the end members and given the proper tension, this being done while the rotary parts are in open position.

What I claim is:

1. In a device of the class described, the combination of a pair of insulated members spaced apart, a rotary member arranged to be moved into alinement with said insulated members, an auxiliary member rotatable with said rotary member for electrically connecting said insulated members, and contacts carried by said members and adapted to be engaged by said auxiliary member.

2. In a device of the class described, the combination of a supporting member and terminal members insulated therefrom and spaced apart, an underrun member pivoted between said terminal members and adapted to be rotated into alinement therewith, a switch blade carried by said underrun member, and contacts on said terminal members adapted to be engaged by the switch blade to electrically connect said terminal members when said underrun member is rotated to alined position.

3. In a device of the class described, the combination of a beam of insulating material and end members attached to said beam adjacent the ends thereof and to which a trolley wire is adapted to be attached, an underrun member rotatably mounted on said beam between said end members and adapted to be rotated in alinement with said end members to form a mechanical continuation thereof, a switch blade mounted on said underrun member and rotatable therewith, and contacts engageable by said switch blade mounted on said terminals.

4. In a device of the class described, the combination of a beam of insulating material and end members attached to said beam adjacent the ends thereof and to which a trolley wire is adapted to be attached, a rotary member mounted on said beam between said end members and adapted to be rotated in alinement with said end members to form a mechanical continuation thereof, a switch blade mounted on said rotary member and rotatable therewith, contacts engageable by said switch blade mounted on said terminals, and a handle outstanding from said rotary member for rotating it and the switch blade.

5. In a device of the class described, the combination of a horizontally disposed beam of insulating material, end members mounted thereon in substantial alinement therewith and spaced apart, a bearing plate fastened to said beam, a rotary member adapted to be positioned in alinement with

said end members and having a corresponding bearing plate, and means yieldingly holding said bearing plates in engagement.

6. In a device of the class described, the combination of a horizontally disposed beam of insulating material, end members mounted thereon in substantial alinement therewith and spaced apart, a bearing plate fastened to said beam, a rotary member adapted to be positioned in alinement with and form a continuation of said end members and having a corresponding bearing plate, means yieldingly holding said bearing plate in engagement, and an angularly outstanding handle on said member for rotating it.

7. In a device of the class described, the combination of a horizontally disposed beam of insulating material, end members mounted thereon in substantial alinement therewith and spaced apart, a bearing plate fastened to said beam, a movable underrun member adapted to be positioned in alinement with said end members and having a corresponding plate, means yieldingly holding said bearing plates in engagement, contact clips mounted on said end members adjacent their inner ends, and a switch blade movable with said movable member for engagement with said clips.

8. In a device of the class described, the combination of a horizontally disposed beam of insulating material, end members spaced apart and bolted to the under edge of said beam adjacent the ends thereof and in substantial alinement therewith, runner pieces formed on said end members and projecting beyond and in alinement therewith for attachment to the trolley wire ends, an intermediate member rotatable into alinement with the end members to mechanically bridge the space therebetween, a relatively large horizontally disposed bearing plate carried by said intermediate member, a fixed corresponding bearing plate fastened to the under edge of said beam, and yielding pivotal means holding said bearing plates in contact.

9. In a device of the class described, the combination of a horizontally disposed beam of insulating material, end members spaced apart and bolted to the under edge of said beam adjacent the ends thereof and in substantial alinement therewith, runner pieces formed on said end members and projecting beyond and in alinement therewith for attachment to the trolley wire ends, an intermediate member rotatable into alinement with the end members to mechanically bridge the space therebetween, a relatively large horizontally disposed bearing plate carried by said intermediate member, a fixed corresponding bearing plate fastened to the under edge of said beam, yielding pivotal means holding said bearing plates in contact, spring contact clips mounted on the upper

edges of said end members adjacent the inner ends thereof, and a switch blade carried by said intermediate member for engaging said clips to electrically connect said end members.

10. In a device of the class described, the combination of a horizontally disposed beam of insulating material, end members spaced apart and bolted to the under edge of said beam adjacent the ends thereof and in substantial alinement therewith, runner pieces formed on said end members and projecting beyond and in alinement therewith for attachment to the trolley wire ends; an intermediate member rotatable into alinement with the end members to mechanically bridge the gap therebetween, a relatively large horizontally disposed bearing plate carried by said intermediate member, a fixed cor-

responding bearing plate fastened to the under edge of said beam, yielding pivotal means holding said bearing plates in contact, spring contact clips mounted on the upper edges of said end members adjacent the inner ends thereof, a switch blade carried by said intermediate member for engaging said clips to electrically connect said end members, and fastening means on said device for attachment to supporting means.
